UNITED STATES PATENT OFFICE

ETIENNE VADASZ, OF STE-CROIX, SWITZERLAND

PHONOGRAPH

Application filed March 29, 1929, Serial No. 350,904, and in Germany August 3, 1928.

My invention relates to improvements in phonographs, and more particularly in phonographs in which the casing is in a form which permits the same to be carried, the said 5 casing being ordinarily in the form of a hand bag or case. One of the objects of the improvements is to provide a phonograph of this type in which the sound arm carrying the sound box is adapted to the form of the casing 10 of the phonograph so that it requires little space. With this object in view my invention consists in constructing the sound arm in curved form disposed around a comparatively large part of the circumference of the turntable carrying the record disk, the said arm extending at least over one quarter of the said circumference, and the dimension of the said sound arm being such that one half of the 15 length of the said sound arm taken from the joint of the sound box to the point where the sound arm is connected with the case is greater than the distance between the sound box or its stylus and said point where the sound arm is connected with the case. There- 20 by the sounds produced by the sound box are effectively transmitted in horizontal and vertical directions though the space required for the sound arm is small, the result being that the entire enlargement from the joint of the 25 sound box to the point where the sound arm is connected with the case can be provided within the sound arm itself, and a flaring horn within the case may be dispensed with.

Further objects of the improvements will 30 appear from the following description.

For the purpose of explaining the invention an example embodying the same has been shown in the accompanying drawings in which the same reference characters have 40 been used in all the views to indicate corresponding parts. In said drawings,

Fig. 1, is a diagrammatical plan view showing the turntable for carrying the record disks, the sound box, and the sound arm,

Fig. 2, is a diagrammatical elevation of the parts shown in Fig. 1, the sound box being in reproducing position,

Fig. 3, is a similar elevation the sound box being in the position removed from the record disk,

Fig. 4, is a perspective view showing a cylindrical casing and the parts shown in Figs. 1 and 2 associated therewith,

Fig. 5, is a sectional elevation showing the casing and its lid and the parts shown in Figs. 1 and 2 associated therewith, and

Fig. 6, is a top plan view of Fig. 5 with the lid removed.

As appears from Figs. 1 and 2, the sound arm 4, 4', carrying the sound box 1 is circular in form, and with the part beginning at the joint of the sound box 1 to the point 2 connected with the sound chamber disposed around a greater part of the turntable 3 which carries the record disks, the said part of the circumference of the turntable being about one half of the circumference, and the sound arm is gradually enlarged in cross-sectional diameter from the joint of the sound box to the point 2. The distance between the sound box 1 and the point 2 is smaller than one half of the total curved length of the sound arm 4, 4', and it is equal to the distance between the point 2 and the centre 5 of the turntable 3. The sound arm is made in two sections 4, 4' connected with each other by a universal joint the axis of which coincides with the axis of the sound arm, so that the section 4' can be rocked either into the plane of the turntable 3 or below the said plane and into inoperative position, and above the said plane into reproducing position. Thus the sound arm requires little room, and the sound waves have a long way through the sound arm from the box 1 to the point 2, so that the gradually flaring form of the path of the sound waves which is necessary for properly amplifying the sound is obtained within the arm 4 itself, and a special sound amplifier at the mouth 2 may be dispensed with.

Fig. 2 shows the section 4' of the sound arm which has been swung relatively to the section 4 into reproducing position in which the sound box 1 bears with its stylus on the turntable 3.

By reason of the novel form of the sound arm the casing of the phonograph may be in the form of a cylinder having a circular bottom 7, a top 8, and a cylindrical wall 9, the diameter of the said casing being com-

paratively small and adapting itself to the novel form of the sound arm. By reason of its cylindrical form the casing can be readily manufactured from sheet metal by a drawing or punching process.

The inner chamber of the casing consisting of the bottom 7, the top 8 and the side wall 9 provides the sounding chamber within which the motor 10 is mounted. The sound is delivered from the said chamber through openings 11 disposed concentrically below the turntable 3, the result being that the said turntable which is disposed the proper distance away from the top 8 of the casing intensifies the sound and directs the same to all sides in horizontal direction.

The lid 12 may be hinged to the casing at 13, any customary means being provided for releasably fixing the lid in the desired position. The record disks to be placed on the turntable 3 may be stored within the said lid.

By disposing the section 4 of the sound arm below the plane of the turntable 3 the said arm requires little room, and the height 25 of the apparatus is comparatively small.

By constructing the sound arm in the manner described above the form of the casing may correspond to the form of the sound arm, and it may be circular in form, so that 30 the height and the diameter of the sound casing are small. Further the cylindrical form of the casing and its lid enclosing the turntable carrying the record disks and the sound arm has a characteristic and artistic appearance.

35 Further, the phonograph may be constructed with a casing which is perfectly closed, and which therefore is not only provided with a bottom plate, but also with a top plate, the said top turntable being provided below the plate carrying the record disks with openings through which the sound 40 is delivered. Thus the said turntable has the function of a sound reflector by means of which the sound is uniformly directed to all 45 sides.

I claim:

1. A phonograph comprising a casing including a sound chamber, a rotatable turntable mounted in said casing for receiving the 50 record disks, a sound arm connected at one end with said sound chamber, said sound arm being of gradually increasing cross-sectional diameter toward its connection with said sound chamber and being of circular 55 form disposed concentrically to a portion of the periphery of said turntable, and a sound box carried by said sound arm at its outer end, one half of the developed length of said sound arm being greater than the distance 60 between its point of connection with the sound box and its connection with the sound chamber.

2. A phonograph comprising a casing including a sound chamber, a rotatable turntable mounted in said casing for receiving the 65

record disks, a curved sound arm lying below said turntable in concentric relation to a portion of the periphery thereof, said sound arm comprising a first section pivotally connected with said sound chamber, and a second section pivotally connected with said first section about an axis substantially parallel with the plane of the sound arm, said section being adjustable out of said plane and being curved to project above said turntable in the 70 adjusted playing position of the sound arm, and a sound box carried by said second section at its free end.

3. A phonograph comprising a cylindrical carrying case consisting of a closed body forming a sound chamber, and a cover movably connected with said body, a turntable mounted in said case for receiving the record disks, a tapering sound arm connected at one end with said chamber and normally lying below said turntable in concentric relation to a portion of the periphery thereof, said sound arm including a movable section arranged to project above said turntable in the adjusted playing position of the sound arm, and a sound box carried by said movable section of the sound arm at its outer end, said sound chamber being provided with sound exit openings located below and in registry with said turntable.

In testimony whereof I hereunto affix my signature.
